United States Patent

Des. 234,485
Patented Mar. 18, 1975

234,485

WORK BENCH

Ronald E. Isles, 623 S. Pine St., Brea, Calif. 92621

Filed May 14, 1973, Ser. No. 360,140

Term of patent 14 years

Int. Cl. D6—03

U.S. Cl. D6—156

FIG. 1.

FIG. 2.

FIG. 3.

FIG. 1 is a front elevational view of a work bench showing my new design;

FIG. 2 is an elevational view of the right side thereof;

FIG. 3 is a rear elevational view thereof; and

FIG. 4 is an isometric view thereof showing the left side thereof.

The left side of the work bench illustrated is a mirror image of the right side thereof.

I claim:

The ornamental design for a work bench, substantially as shown and described.
